UNITED STATES PATENT OFFICE.

LOUIS H. HAYS, OF CLEVELAND, OHIO, ASSIGNOR TO THE KAYNEE COMPANY, OF CLEVELAND, OHIO, A CORPORATION OF OHIO.

GARMENT.

1,113,008.

Specification of Letters Patent.

Patented Oct. 6, 1914.

Application filed June 29, 1912. Serial No. 706,633.

To all whom it may concern:

Be it known that I, LOUIS H. HAYS, a citizen of the United States, and a resident of Cleveland, county of Cuyahoga and State 5 of Ohio, have invented a new and useful Improvement in Garments, of which the following is a specification, the principle of the invention being herein explained and the best mode in which I have contemplated 10 applying that principle, so as to distinguish it from other inventions.

The present invention relates in general to garments, and in particular it provides a blouse adapted to be easily and conveniently drawn tightly around the waist of the wearer and to be free of surplus material about the waist.

To the accomplishment of the foregoing and related objects, said invention, then, 20 consists of the means hereinafter fully described and particularly pointed out in the claim.

The annexed drawing and the following description set forth in detail a certain construction embodying the invention, such disclosed means constituting, however, but one of the various constructions in which the principle of the invention may be used.

In said annexed drawing the figure is an 30 elevational view of a garment embodying the invention.

The invention provides, in a blouse provided with the usual arm-holes 1 and the arms 14 secured thereover, a body portion 35 formed by a front 2 and a back 3, and this body portion, formed by the front and back, is of increasing width from the bottoms 4 of the arm-holes downwardly for a part of its length, as at 5. The waist line 6 of the blouse, however, is of less width than the lower end of the part 5, and the sides of the body portion are gradually curved inwardly 40 from the bottom of the part 5 to the waist line, as at 7. At the waist line, the blouse is provided with a hem 8 provided with open 45 ends 9 at the front of the garment, the blouse being open at its front. The hem 8 is provided with an open slot 10 at a point somewhat removed from the front of the blouse, while in the hem is disposed a single 50 cord, the ends 11 of which are turned up near the front of the garment so that they are crossed by the seam 12, the cord being thus permanently secured within the hem, 55 while a portion of the cord is adapted to

project outwardly through the slot 10 to form a loop 13.

In use, the blouse is donned by the wearer, who may, himself, then pull a portion of the cord in a loop through the slot in the hem 60 and tie the loop into a knot, thus securing the garment snugly around the waist of the wearer. The body portion being of increasing width for the greater part of its length will be comfortably loose, as is desired in a 65 garment of this sort, but because the sides are curved inwardly to the narrower waist line, the garment will more accurately conform with the waist measurement of the wearer, and the usual bulky and unsightly 70 surplus material at the wearer's waist is eliminated. The invention thus provides a blouse adapted to be drawn securely around the wearer's waist, which, although it has sufficient width on the waist line to render 75 it easy of adjustment, nevertheless, is free from needless material. The blouse, therefore, is one easy of adjustment and neat and comfortable after adjustment, and, because of the peculiar construction provided by the 80 slotted hem and single adjusting cord, the garment may be removed and donned by the wearer without changing the adjustment.

The part 5 of the body portion is made of substantially uniform width, if desired, 85 instead of increasing width, but nevertheless the waist-line is of less than such uniform width and the body portion is curved at its sides from the bottom of such part inwardly to the waist-line. Whether the preferred form with body of downwardly increasing width, or a body of uniform width, 90 be used, the width at the waist-line is less than the width of the remainder of the body portion and the latter is tapered at its sides 95 for the lower part of its length into the waist-line.

Other modes of applying the principle of my invention may be employed instead of the one explained, change being made as regards the construction herein disclosed, provided the means stated by the following claim or the equivalent of such stated means be employed.

I therefore particularly point out and distinctly claim as my invention:—

An open-front blouse formed with arm-holes, and having a body portion so cut that it increases in width from the bottom of the arm-holes downwardly for part of its length 110

and is curved at its sides from the bottom of said part inwardly to the waist-line, the blouse being of less width at the waist-line than at the bottom of said part and being provided at the waist-line with a hem having open ends at the front and an open slot at a point removed from the front, in combination with a single cord disposed in said hem and having its ends secured near the

front by the seam of the hem, a portion of said cord being adapted to project through said slot in the form of a loop.

Signed by me this 27th day of June, 1912.

LOUIS H. HAYS.

Attested by—

ROBERT M. SEE,
HELEN R. POST.
